UNITED STATES PATENT OFFICE.

HUGO V. MANN-TIECHLER, OF MUNICH, GERMANY.

SCARF-HOLDER.

SPECIFICATION forming part of Letters Patent No. 430,191, dated June 17, 1890.

Application filed June 7, 1889. Serial No. 313,503. (No model.)

To all whom it may concern:

Be it known that I, HUGO VON MANN-TIECHLER, a resident of Munich, Bavaria, German Empire, have invented a new and 5 useful Improvement in Scarf-Holders, of which the following is a specification.

This invention relates to a scarf-holder of improved construction; and it consists in the various features of improvement more fully 10 pointed out in the claim.

In the accompanying drawings, Figure 1 is a rear view of my improved scarf-holder, and Fig. 2 a vertical section on line *y y*, Fig. 1.

The letter *A* represents a scarf, to which is 15 stitched a plate *a*. To this plate is secured a threaded pin *f*, which projects into an **L**-slot of a second plate *d*. The vertical part of this slot is marked *e*, and the horizontal or

open part of the slot is marked *e'*. To the plate *d* there is hinged by hinge *C* an eye *C*. 20

In use the eye is passed over the collar-button before the collar is buttoned. After the collar and scarf are in place the pin *f* is slipped into the **L**-slot and is clamped at any desired elevation by a nut *f'*. 25

What I claim is—

The combination of plate *a*, having pin *f*, with slotted plate *d*, having hinged eye *C*, and with the nut *f'*, substantially as specified.

In testimony whereof I have signed this 30 specification in the presence of two subscribing witnesses.

HUGO V. MANN-TIECHLER.
